UNITED STATES PATENT OFFICE.

WILLIAM F. ANDERSON, OF COLORADO SPRINGS, COLORADO.

MACHINE FOR REBORING ENGINE-CYLINDERS.

1,238,478.

Specification of Letters Patent. Patented Aug. 28, 1917.

Application filed August 16, 1916. Serial No. 115,146.

To all whom it may concern:

Be it known that I, WILLIAM F. ANDERSON, a citizen of the United States, residing at Colorado Springs, in El Paso county, in the State of Colorado, have invented certain new and useful Improvements in Machines for Reboring Engine-Cylinders, of which the following is a specification.

My invention relates to improvements in machines for reboring engine cylinders. My invention has for its object to produce such a machine by combining an attachment which I have devised with the ordinary engine lathe. It is well known that in order to keep an automobile engine or other gasoline engine in perfect working condition it is necessary to rebore the cylinders occasionally. This work has heretofore been done by a boring machine which can be used for the purpose of boring only. Such machines are so expensive and capable of such limited use that they have not been installed in ordinary automobile repair shops and garages. It is therefore in most cases necessary for automobile repair shops to send engine cylinders to the manufacturer when reboring is required.

By combining my attachment with an ordinary lathe, a machine is produced which is capable of performing a function of the cylinder boring machine. The attachment by means of which I convert a lathe into a reboring machine is so inexpensive to manufacture that it is within the reach of every repair shop and garage, and such shops may by use of it eliminate the expense and delay heretofore necessitated by sending cylinders to the manufacturer when reboring is required.

40 By using my machine, it is possible to rebore cylinders cast in block as well as those cast separately.

The embodiment of my invention is illustrated in the accompanying drawings, in which:

Figure 1 is a side view of the attachment by means of which I convert a lathe into a cylinder boring machine, showing the position of the cylinder to be rebored in dotted lines;

Fig. 2 is a front elevation of my attachment;

Fig. 3 is a top view of my attachment;

Fig. 4 is a bottom view of my attachment;

55 Fig. 5 is a perspective view of my reboring machine showing the attachment com-

bined with a lathe and showing the position of the cylinder to be rebored in dotted lines;

Fig. 6 is a fragmentary longitudinal section taken along the axis of the spindle 18 and shaft 19 shown in Fig. 5.

Fig. 7 is a rear elevation of my attachment.

I will first describe my attachment as illustrated in detail in Figs. 1, 2, 3, 4, 7: The frame of the attachment consists of a bottom 1 having the strengthening rib 2; the wall 3 having the strengthening ribs 4 and 5; and the posts 6 and 7 having strengthening ribs 65 8 and 9. The frame comprising these parts preferably consists of a single piece of metal. To the bottom of the frame are bolted the pieces 10 having the grooves 11 adapted to fit over the ways of a lathe. The bolt holes 75 12 in the pieces 10 are extended laterally so that the grooves 11 are capable of sidewise adjustment. This makes the attachment adaptable to lathes in which the ways are different distances apart. 80

The wall 3 is provided with a central opening 13. Threaded holes are provided in the tops of the pieces 6 and 7, through which pass screws 14 whose ends engage small holes in the block 15. A bar 16 is attached 85 to the wall 3 and extends rearwardly therefrom.

I will now describe my complete reboring machine, which consists of a lathe in combination with an attachment which I have 90 described and certain other features:

Fig. 5 shows the lathe 17. Upon the head spindle 18 of the lathe is attached the centering head 19, which consists of a piece of steel one end of which tapers gradually from the 95 diameter slightly larger than that of the cylinder to be rebored to a diameter slightly smaller than that of the cylinder. Beyond the centering head is a shaft 20 attached to the head spindle 18, and supported at its 100 outer end upon a center 21, attached to the tail stock 22 of the lathe. Upon the shaft 20 is the reboring tool or reamer 23.

As shown in Fig. 5, my attachment is placed with its grooves 11 upon the ways 105 24 of the lathe. The rear end of the bar 16 is attached to the tool holder 25, which is carried by the tool carriage 26 of the lathe.

The operation of my reboring machine is 110 as follows:—

Before the shaft 20 and reamer 23 are

placed in position, the casting containing the cylinder to be rebored is placed upon the bottom 1 of the attachment and is propped up so as to maintain the center of the cylinder slightly below the center of the head stock and tail stock of the lathe. The attachment bearing the cylinder casting is then moved along the ways of the lathe toward the head stock by moving the tool carriage, until the centering head enters and centers the cylinder to be bored. While the centering head is in the cylinder the screws 14 are screwed in, gripping the cylinder between the wall 13 and the bars 15 and thus holding it in proper position to be bored. The attachment bearing the cylinder is then moved away from the head stock by moving the tool carriage, and the shaft 20 and reamer 23 are placed in the position shown in Fig. 5. The reamer is then rotated by rotating the head spindle of the lathe and the cylinder is fed against the reamer by moving the tool carriage forward. The cylinder is fed forward until the reamer is passed completely through it and is thus accurately rebored.

What I claim is:—

1. A reboring machine comprising a lathe having ways, a head stock, a tail stock, and a tool carriage; an attachment for holding the casting to be rebored having grooves fitting upon said ways; a bar connecting said attachment with said tool carriage; and a reamer carried between said head stock and tail stock.

2. A reboring machine comprising a lathe having ways, a head stock and head spindle, a tail stock, and a tool carriage; a device for holding the casting to be rebored, having grooves fitting upon said ways; a bar connecting said attachment and said tool carriage; and a tapering centering head attached to said head spindle.

3. A reboring machine comprising a lathe having ways, a head stock and head spindle, a tail stock, and a tool carriage; an attachment adapted to hold the casting to be bored

and having grooves fitting upon said ways; a bar connecting said attachment with the tool carriage of said lathe; a tapering centering head upon said head stock; a shaft supported between said head stock and said tail stock and attached to said head spindle; and a reamer fixedly mounted upon said shaft.

4. A reboring machine comprising a lathe having ways, a head stock, a tail stock, and a tool carriage; an attachment having a bottom with grooves fitting upon said ways and a wall perpendicular to said grooves, and an adjustable means for pressing the casting to be bored against said wall; and a bar rigidly connecting said wall with said tool carriage.

5. A lathe attachment comprising a bottom having grooves adapted to fit upon the ways of the lathe, a wall perpendicular to said grooves, and means for pressing a casting against said wall.

6. A lathe attachment for reboring cylinders, comprising a bottom having grooves adapted to fit upon the ways of the lathe, a wall perpendicular to said grooves near one end of said bottom, posts near the other end of said bottom, blocks adjacent to the inner sides of said posts, and means co-acting with said posts for forcing said blocks toward said wall.

7. An attachment for lathes, comprising an integral frame consisting of a bottom, a wall at one end of said bottom, and posts at the other end thereof, and grooved pieces adapted to fit upon the ways of the lathe adjustably attached to said bottom.

8. A lathe attachment for reboring cylinders, comprising a frame having a bottom with grooves adapted to fit upon the ways of the lathe, a wall perpendicular to said grooves, means for pressing the casting to be bored against said wall, and a bar attached to said frame and adapted to be fastened to the tool carriage of the lathe.

WILLIAM F. ANDERSON.
